Inventor:

Francis R. Donahue
by his Atty's:
Philip George Rice Kennedy

UNITED STATES PATENT OFFICE.

FRANCIS R. DONAHUE, OF WATERBURY, CONNECTICUT, ASSIGNOR TO SCOVILL MANUFACTURING COMPANY, OF WATERBURY, CONNECTICUT, A CORPORATION OF CONNECTICUT.

VANITY CASE.

Application filed May 9, 1925. Serial No. 29,008.

To all whom it may concern:

Be it known that I, FRANCIS R. DONAHUE, a citizen of the United States, residing at Waterbury, county of New Haven, and State of Connecticut, have invented certain new and useful Improvements in Vanity Cases, fully described and represented in the following specification and the accompanying drawings, forming a part of the same.

10 This invention relates to certain improvements in small boxes or cases for holding loose powder, now commonly known as vanity cases.

In certain types of these cases there is 15 provided a case or box having a bottom and a cover, usually pivotally associated, the bottom forming a compartment for loose powder. This compartment is provided with a fitment formed with a central aperture, 20 and this central aperture is closed by a spring actuated plate, the powder being extracted from this compartment by lightly tapping this plate against the spring.

These springs have usually been associated 25 with the plate either loosely or by riveting or soldering. Where they were loosely associated the user had some trouble in reassembling the parts after the fitment was taken out for the refilling of the box with 30 powder. Riveting is expensive and difficult to do, particularly where the spring is in the form of round wire. Soldering is disadvantageous, in that it is difficult to do and makes an unattractive piece of work 35 and is liable to corrode.

It is the special object of the present invention to produce an improved means for assembling the fitment, the distributing plate, and the spring so that these parts may 40 be taken from the box as a unit in refilling, and in which no solder or rivets are used.

With this and other objects not specifically referred to, the invention consists in certain novel parts, arrangements and combinations which will be fully described in connection with the accompanying drawings and the novel features pointed out in the claims hereunto annexed.

In these drawings,—

50 Figure 1 is a face view of the box, the parts being shown in open position;

Figure 2 is a vertical section taken on the line 2—2 of Fig. 1 on a little larger scale;

Figure 3 is a sectional plan view taken on the line 3—3 of Fig. 2, and

Figure 4 is a detail sectional view of the removable part of a fitment.

Figure 5 is a perspective view of the spring for holding the distributing plate in position.

Referring now to these drawings, the box selected to illustrate the invention is one of the usual metal boxes, shown as circular. This shape, however, is conventional and the invention is not to be limited to such a shaped box. The box illustrated includes a body or bottom 1 having side walls 2, this box being closed by a cover 3 pivotally associated with the box body by a hinge 4. The side walls of the box are inset to form a shoulder 5 and a flange 6, with which telescopes a flange 7 on the cover 3, the flange abutting against the shoulder 5 when in closed position. The cover, if desired, may be provided with a mirror 8 held in position 75 by the usual bezel 9.

Located in the bottom of the box is a fitment, which in the best constructions includes a part which is fixed in the box and a part which may be readily removed to 80 permit the box to be refilled, and the parts of this fitment will be constructed so as to be substantially powder tight. In the particular construction shown this fitment includes an annular member having an outer 85 depending flange 10 which rests on the bottom of the box. This flange is slit at opposite sides to form spring projections 11 which are bent outward slightly so that they will snap under the shoulder 5, before referred to, and hold the member securely in the box. This member is or may be formed with a slightly flattened portion 12 from which extends inwardly and downwardly a wall 13, this wall 13 being continued vertically, as shown at 14. Cooperating with the fixed annular member is a removable member, this removable member having a snug friction fit so as to prevent powder from accidentally escaping therefrom. As 90 shown, this removable member includes a plate having a wall, the upper portion of which is inclined or bevelled, as indicated at 95 15 in Fig. 4, the inclination of this wall corresponding to the inclination of the upper part of the wall 13 of the fixed member.

The wall 15 is continued vertically, as shown at 16, this vertical part of the wall having a snug friction fit within the lower wall 14 of the fixed member. This construc-

tion effects a close friction fit and prevents leakage of powder between the two members. If desired, the wall of the fixed member may be provided with a depression 17 under which the thumb nail or a suitable tool may be slipped to disengage the removable member from the fixed member.

This removable member is provided with a central partition 18 which is sloped gradually downward, as shown in Fig. 4, and is formed with a central distributing opening 19. This opening is closed by a flat plate 20 which is held close against the under surface of the partition 18 by means of a spring 21. In accordance with the invention, this spring, the plate, and the removable part of the fitment are associated so that they can be removed from the box as a unit without the use of riveting or soldering, and in the best constructions the spring will be a coiled spring, as with such a spring the parts can be cheaply and readily associated in the manner desired.

While this may be effected in various ways, in the particular construction illustrated the removable member, below the partition 18, is provided with integral holding devices which engage a coil of the spring and hold the spring firmly in position, the loose end of the spring bearing against the bottom of the plate, as shown in Fig. 2. While this may be accomplished in various ways, in the particular construction illustrated the wall 16 of the removable member is slit, as indicated at 22' in Fig. 4, and preferably on opposite sides, as shown in Fig. 3, to provide spring tongues, which may be bent upwardly to enclose a coil of the spring. As shown, there are two of these spring tongues, 22, 23, one of the tongues, as 22, holding the end of the spring 24 of the spring helix, and the other, 23, holding the coil on the opposite side. The free end 25 of the helix bears against the bottom of the plate.

With this construction the removable member, the distributing plate, and the spring can be readily and cheaply associated in a unitary structure of neat appearance,

and in which the use of rivets or solder is 50 obviated. While the particular means shown for holding the spring in position is a convenient one, it will be understood that other means can be devised within the scope of the invention, and the invention, therefore, is not to be restricted to the exact construction shown and described.

What I claim is:

1. In a vanity box, the combination of a body and a cover, a fitment in the body having a distributing opening, a plate closing the opening, a spring bearing at one end against the plate and tending to press the plate into engagement with the fitment, and means integral with the fitment for associating the spring therewith, whereby the fitment, the plate and the spring may be removed from and replaced in the box as a unit.

2. In a vanity box, the combination of a body and a cover, a fitment in the body having an opening and provided with a depending flange, a plate closing below the opening, a spring bearing at one end against the plate and tending to press the plate into engagement with the fitment, and holding clips formed by slitting and bending up portions of the flange for engaging the spring and positively associating it with the fitment, whereby the fitment, the plate and the spring may be removed from and replaced in the box as a unit.

3. In a vanity box, the combination of a body and a cover, a fitment in the body having an opening and a depending flange, a plate closing the opening, a helical spring bearing at one end against the plate and tending to press the plate into engagement with the fitment, and clips formed by slitting the flange and bending it up around a coil of the spring for positively associating the spring and the fitment, whereby the fitment, the plate and the spring may be removed from and replaced in the box as a unit.

In testimony whereof, I have hereunto set my hand.

FRANCIS R. DONAHUE.
